MAGNETIC STACKING MECHANISM

Robert T. Chatterton, Wappingers Falls, N. Y.,
assignor to American Can Company, New York,
N. Y., a corporation of New Jersey

Application December 30, 1947, Serial No. 794,708

4 Claims. (Cl. 214—6)

1

The present invention relates to a stacking mechanism for arranging in a stack metal articles, such as can or container end closures and has particular reference to magnetic devices for guiding and arranging the articles in an orderly stack.

In the automatic high speed feeding of articles especially flat articles into stacks for subsequent refeeding, an article occasionally enters upon the stack in an angular or irregular position with relation to the other articles in the stack and thereby causes disorderly assembly or jams which cause interruption of the feeding operation or prevent succeeding articles from being properly arranged in the stack.

The instant invention contemplates overcoming these difficulties by the provision of a magnetic device which provides for guiding the articles into proper position as they fall into place on a stack.

An object of the invention is the provision in a stacking mechanism for flat articles of devices wherein the articles as they are received for stacking are guided into a proper position prior to and during their fall onto the stack so that they will arrive on the stack in correct relation to the other articles in the stack.

Another object is the provision of such a stacking mechanism wherein one or more of the articles being stacked are held in guided suspension over the stack for properly receiving the articles to be stacked and for lowering the articles onto the stack in orderly relation.

Another object is the provision of such a stacking mechanism wherein the orderly reception and the proper positioning of the articles in the stack is effected magnetically and in such a manner as to handle the articles individually so that scratching or otherwise marring of coated or decorated surfaces may be prevented.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a feeding and stacking mechanism embodying the instant invention, with parts broken away;

Fig. 2 is a sectional view taken substantially along the line 2—2 in Fig. 1, with parts broken away and with parts shown in elevation;

Fig. 3 is a view similar to Fig. 2 and showing a modified form of the invention; and

2

Fig. 4 is a wiring diagram of the electromagnetic system used in the mechanism.

As a preferred and exemplified embodiment of the instant invention, Figs. 1 and 2 illustrate a mechanism for feeding and stacking circular sheet metal can ends or closures A for refeeding into an automatic machine for subsequent treatment. The can ends A are received from any suitable source of supply, on an endless belt conveyor 11, the machine end of which operates over a pulley 12 mounted on a horizontal shaft 13 carried in bearings 14 formed in a frame 15 which constitutes the main frame of the stacking mechanism. The conveyor shaft 13 is rotated by an endless chain 16 which operates over a driven sprocket 17 carried on the shaft, and over a driving pinion 18 carried on a rotor shaft 19 of an electric motor 21 bolted to the frame 15.

The can ends A are delivered individually by the conveyor 11 into an inclined chute 24 secured to a bracket 25 of the frame 15 adjacent the conveyor pulley 12. The lower terminal end of the chute is formed with a vertically disposed cylinder 27 having open top and bottom ends. The bottom end of the cylinder rests on and is in vertical alignment with a nonmagnetic vertical guide sleeve or hopper 28 having at its lower end a flange 29 secured in a feed housing 31 bolted to the frame 15.

The can ends A received in the chute 24 fall through the cylinder 27 and form a vertical stack B in the hopper 28. The ends are preferably refed individually from the bottom of this stack, for subsequent treatment, by a conventional feeding device which includes a separator screw 33 and a feed finger 34 such as disclosed in United States Patent 2,172,402 issued September 12, 1939, to R. E. J. Nordquist on Can Treating Machine and Feed Control Therefor.

In such a feeding device, the lowermost can end A in the stack B rests on a lug or shoulder 36 formed in the housing 31 and on an oppositely disposed rotatable barrel 37 of the separator screw 33. The screw barrel is secured to a vertical shaft 38 journaled in a bearing 39 formed in the housing 31. The shaft is rotated in any suitable manner. The outer periphery of the screw barrel is formed with an inclined slot 41. Above the barrel, the shaft 38 carries a cut off or separator knife 42.

Hence as the screw barrel 37 rotates with the shaft 38 in time with other moving parts the separator knife 42 cuts in between the lowermost can end A and the can end next above and thus temporarily supports the stack above the lower-

most can end. With the stack thus supported the edge of the lowermost can end on the barrel 37 falls into the inclined slot 41 and hence rides down along this slot into the inclined position shown in Fig. 2, separated from the rest of the stack. While in this position the feed finger 34 engages behind the separated can end and sweeps it out from under the stack and carries it along the usual guide rails to any suitable place of deposit. For this purpose the feed finger 34 is mounted on the upper end of a vertical shaft 45 which is journaled in a bearing 46 formed in the housing 31. The shaft is rotated in any suitable manner in time with the separator screw shaft 38.

The can ends A as they fall into the hopper 28 are magnetically controlled so as to insure proper guiding and positioning of the can ends on the stack. For this purpose the hopper 28 is surrounded by a pair of bar electromagnets 48 which are energized by the flow of electric current in the proper direction through a pair of coils 49 interposed between the magnets at their opposite ends as shown in Fig. 1. In other words, the bar 48 to the left (Fig. 1) is north (N) as shown and the bar 48 on the right marked "S" is the south pole. This sets up a magnetic field across the hopper and the ends moving therethrough. The effect of this arrangement is the provision of two oppositely disposed horseshoe magnets. Each coil 49 sets up a magnetic field of its own and since there are two coils disposed on opposite sides of the hopper 28, there are two separate magnetic fields entering the hopper, the lines of force of one magnetic field combining with the lines of force of the other magnetic field in an extended widely distributed pattern of supporting flux. These magnets are supported on a non-magnetic collar 51 which surrounds the lower end of the hopper and which is interposed between the bottoms of the magnets and the feed housing 31. Adjacent the hopper 28, the magnets are recessed to fit around the hopper. The inner surfaces 50 of these recesses are tapered downwardly and outwardly as shown in Fig. 2 providing a greater distance for the lines of magnetic flux of magnetic force passing between the magnets of opposite polarity as viewed from top to bottom. The space within the hopper, therefore, which is located between the pole faces of magnets may be considered as consisting of a plurality of layers or strata. These layers or magnetic lines of force, in the embodiment now being considered, have different flux densities. Obviously since the shorter distance between the pole faces of the magnets for the conduction of the magnetic flux is at the top edges of the magnets, the greatest intensity of the field is at the top edges of the magnets surrounding the top of the hopper where the can ends enter.

Hence when a can end A is delivered by the conveyor 11 into the chute 24, it slides down the chute and into the cylinder 27 and drops into the magnetic field in the hopper 28. As the first can end enters this magnetic field, the magnetic lines of force extending across the hopper act on the falling can end and bring it into a horizontal balanced position and hold it suspended temporarily at the top edges of the magnets where the intensity of the field is at its maximum.

A subsequently fed can end A as it slides down the chute 24, falls on top of the suspended can end, the suspended can end acting as a guide for the proper horizontal delivery of the subsequent can end. In this manner as each can end

from the chute 24 falls into place on the stack, the other can ends settle down in the hopper 28. The magnet coils 49 preferably are of sufficient strength to maintain only a predetermined number of can ends A in suspension in the hopper 28, substantially as shown in Fig. 2. Under normal operation of the mechanism one can end A will drop from the bottom of the magnetic field and fall properly onto the top of the stack each time an entering can end is delivered from the chute 24 into the top of the field at its point of maximum intensity. The top can end of the suspended ends within the hopper always serves as a guide for an incoming can end. In this manner continuous and smooth operation of the mechanism is insured. If for any reason the can ends are fed into the hopper too rapidly or if they are not discharged from the bottom of the hopper fast enough the can ends in the hopper build up until the hopper is filled with a solid stack, the top can end always serving as a guide for an incoming can end.

When the hopper 28 is filled to capacity, the can ends on top of the stack project above the magnets 48 and engage against and operate a movable switch arm 55 disposed in a slot 56 in the chute cylinder 27 and carried on a pivot pin 57 secured in the cylinder. This arm engages against and actuates the movable element of a normally closed electric stack or micro-switch 58 secured to the chute cylinder 27 and electrically connected to the electric motor 21. The opening of this switch stops the motor 21 and the conveyor 11 and thus stops further feeding of can ends into the hopper 28 until the stack of can ends is nearly exhausted by the feeding device at the bottom of the stack. Restarting of the motor and the conveyor is controlled by a time delay device 61 (Fig. 4) which is regulated to operate in accordance with the speed of feeding of the can ends from the bottom of the stack.

As the can ends are removed from the bottom of the stack, the stack decreases in size but always a few of the uppermost can ends in the stack will remain temporarily suspended in the hopper in the region of the magnets 48 as shown in Fig. 2. In this portion of the hopper, the uppermost can end will remain in suspension at the upper edge of the magnets where the intensity of the magnetic field is at its maximum and thus this suspended can end will be ready to serve as a guide for subsequently entering can ends, when the motor 21 and conveyor 11 resume operation to replenish the stack.

The time delay device 61 preferably is of the dash pot type in which a piston 71 (Fig. 4) contained in a cylinder 72 falls slowly against the resistance of air controlled by a vent valve 73 in the bottom of the cylinder. The valve is set to permit the piston to fall in a predetermined length of time and also allows the piston to be lifted quickly. Lifting of the piston is effected by an electric solenoid 74 which surrounds a core section of a rod 75 which constitutes the piston rod.

Referring now to the wiring diagram in Fig. 4 it will be seen that the coils 49 of electromagnets 48 preferably are connected in parallel by wires 77, 78 to main lead wires 79, 80 of a source of electric current such as a battery or generator 81. It is through this connection with the source of current that the magnets are maintained in an energized condition.

The electric motor 21 controlled by the micro-switch 58 is excited through an operating circuit

which includes the electric solenoid 74 of the time delay device 61 which is normally energized and a time delay switch 83 which is normally closed. In this circuit, the lead wire 80 of the source 81 of current is connected by a wire 84 to one side of the stack switch 58. The opposite side of this switch is connected by a wire 85 to the motor 21. The motor is also connected by a wire 86 to one side of the delay solenoid 74. The opposite side of this solenoid is connected by a wire 88 to the lead wire 79 of the source of current. Hence when the stack switch 58 is closed, electric current flows through this circuit and operates the motor 21 and also energizes the solenoid 74 and thus holds the delay switch 83 closed and retains the piston 71 in a raised position in its cylinder.

When the stack of can ends A reaches a height sufficient to open the stack switch 58, the circuit is broken. Thus the motor 21 stops operating and the delay solenoid 74 is immediately de-energized. The de-energization of the solenoid releases the piston 71 and permits it to fall slowly through its delay cycle until it reaches the bottom of the cylinder. As the piston falls, it opens the delay switch 83 so that the circuit O cannot again be re-established by the closing of the stack switch 58, until the piston has fully completed its time delay cycle.

During this time delay cycle, the feeding of the can ends from the bottom of the stack, decreases the height of the stack and thus permits the stack switch 58 to close. However nothing happens because the delay switch 83 remains open and thus the circuit remains broken. Upon the completion of the time delay cycle, the delay solenoid is re-energized and this quickly raises the piston and closes the delay switch 83 to restart the motor. This re-energizing of the solenoid 74 is effected through a separate restarting circuit R which includes a normally closed electric switch 91 and a normally open electric switch 92 which are actuated by engagement with a projection 93 on the piston rod 75.

When the piston is in a raised position as shown in Fig. 4, the projection 93 engages the normally closed switch 91 and holds it open. However when the piston is released and falls in its cylinder, the projection moves away from the switch and permits the switch to close. When the piston reaches the bottom of the cylinder, the projection engages and closes the switch 92. Hence with both of these switches 91, 92 closed electric current flows from the wire 84 along a connecting wire 94, through closed switch 92, along a wire 95, through closed switch 91, along a connecting wire 96, through a solenoid 97 having a movable core 98, and along a connecting wire 99 to wire 88 and then to the lead wire 79. Electric current flowing along this circuit R energizes the solenoid 97 and thereby closes a double switch 101, 102 connected to the movable core 98 of the solenoid and thereby establishes two new circuits, an energizing circuit S and a holding circuit T.

The closing of the energizing circuit S permits electric current to flow from the wire 84, through the closed stack switch 58, wire 85, motor 21, wire 86, solenoid 74, wire 87, a connecting wire 105, closed switch 101, a connecting wire 106, returning to the lead wire 79. This circuit excludes the open delay switch 83 but energizes the delay solenoid 74 so as to raise the piston 71 and it also restarts the motor 21 to begin feeding of can ends onto the stack to replenish the stack. However as soon as the piston

begins the rise, the projection 93 on the piston rod rides off the switch 92 and permits this switch to open. The opening of this switch has no effect on the solenoid 97 since electric current now flows along the holding circuit T from the wire 84, along wire 94, a connecting wire 108, closed switch 102, a connecting wire 109, wire 95, closed switch 91, wire 96, solenoid 97, wires 99, 88, returning to the lead wire 79. Thus current flowing through this holding circuit T keeps the solenoid 97 energized while the piston is rising to its upper limit to close the delay switch 83.

When the piston reaches its upper limit of travel and closes the delay switch 83, the flow of current through the delay solenoid 74 is transferred through the regular operating circuit O, along the wire 87, switch 83, and wires 88, 79. The holding circuit T and the energizing circuit S are then broken. This is effected by the projection 93 on the piston rod 75, coming into engagement with and opening the switch 91 just as the piston reaches its upper limit of travel and closes the delay switch 83. The opening of this switch 91 opens all of the other circuits R, S, T, excepting the operating circuit O and thereby returns the entire system to its original condition. The projection 93 holds the switch 91 open to maintain this condition until the stack of can ends again reaches a height sufficient to open the stack switch 58 and thereby repeat the operations just explained.

As a modified form of the invention Fig. 3 illustrates a stacking mechanism which is similar to the mechanism explained hereinbefore except that the inner faces of the magnets 48 are parallel instead of being tapered as in the preferred form shown in Fig. 2. In such a modified form of the mechanism, a can end A as it slides off the entrance chute 24 and drops through the cylinder 27, falls into a magnetic field of equal intensity for the full depth of the magnets surrounding the hopper 28. This magnetic field extends across the hopper at an angle thereto, preferably of right angles to the travel of the can ends through the hopper.

The effect of this magnetic field on the entering can end is to bring the can end into a horizontal position parallel with the lines of force of the magnetic field, as it enters the hopper unguided, and to slow down its falling action, thereby permitting the can end to slowly and gently settle into a proper position on top of the stack B. No suspended can ends are necessary to guide the incoming ends into a horizontal position, as in the preferred form of the invention.

Such a modified form of the mechanism is advantageous where the can ends are coated, decorated or lithographed and it is desired to prevent sliding of one end over another which might scratch or otherwise mar the surface. In this modified form of the invention the control of the replenishing of the stack, as the ends are fed from the bottom thereof, is effected in the same manner and by similar electric circuits as explained hereinbefore for the preferred form.

The invention is not limited to a hopper which terminates in an end feed. The end feed could be omitted and the hopper used as an accumulator or counter of stacked articles for packing or depositing the stacked articles in a complete unit. Numerous other applications of the invention will occur to those who wish to utilize the same.

It is thought that the invention and many of

its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a mechanism for stacking magnetizable articles having a flat extensive area such as can ends or the like, the combination of a hopper for receiving a plurality of the articles at the top portion thereof and for accumulating them in stacked position at the bottom portion thereof, means for feeding said articles individually into said hopper, a plurality of magnets substantially surrounding said hopper, each magnet having a field of its own and the fields of all magnets continuously linking with the moving articles in said hopper thereby widely distributing the lines of force of said fields in said articles for balancing and maintaining in substantial parallelism articles entering said hopper for controlling their travel through the hopper into proper position in stacked relation.

2. In a mechanism for stacking magnetizable articles having a flat extensive area such as can ends or the like, the combination of a hopper for receiving a plurality of the articles and for retaining them in stacked position, means for feeding said articles individually into said hopper, a pair of magnet bars located in opposition to each other and extending past said hopper on opposite sides thereof, said bars adjacent said hopper having shaped portions substantially conforming to the contour of a portion of said articles, and a pair of magnet coils disposed between adjacent ends of said magnet bars for setting up like poles at opposite ends of each of said bars for creating in said hopper and said moving articles magnetic fields having at said shaped portions of said bars widely distributed and balanced lines of force for balancing and supporting in substantial parallelism articles entering said hopper for controlling their travel through the hopper into proper position in stacked relation.

3. In a mechanism for stacking flat magnetizable articles such as can ends or the like, the combination of a nonmagnetic hopper for receiving a plurality of said flat articles and for accumulating them in stacked position, means including an inclined chute connecting with the top end of said hopper for feeding said articles individually into said hopper in a near horizontal position, at least a pair of magnets substantially surrounding said hopper, said magnets hav-

ing portions of their inner faces shaped in substantial conformity with adjacent peripheries of said articles in the hopper, said faces adjacent said hopper tapering outwardly and downwardly from their upper edges, each of said magnets providing a magnetic field extending into said hopper and said moving articles, said fields having at the shaped portions of said magnets widely distributed and balanced lines of force for balancing and supporting parallel articles entering said hopper, said tapered faces providing at their upper edges the maximum flux density of said fields for temporarily holding an article in suspension as a guide and temporary support for the next incoming article entering said hopper and for suspending in spaced relation other articles in said hopper for gradual lowering and positioning in stacked relation at the bottom of said hopper as incoming articles enter said hopper at its top end.

4. In a mechanism for stacking magnetizable articles having a flat extensive area such as can ends or the like, the combination of a hopper for receiving a plurality of the articles at the top portion thereof and for accumulating them in stacked position at the bottom portion thereof, means for feeding said articles individually into said hopper, a plurality of magnetizable bars substantially surrounding and conforming to the peripheries of adjacent articles in said hopper, means for magnetizing said bars to set up mutually repellent magnetic fields around said bars and entering said hopper, the lines of force of said fields combining in an extended widely distributed pattern of supporting flux to effect continuous linking with the moving articles in said hopper in widely distributed lines of force in said articles to balance and maintain in substantial parallelism articles entering said hopper and for controlling their travel through the hopper into proper position in stacked relation.
